A. FERNALD,
RIGHT ANGLE NERVE EXTRACTOR.
APPLICATION FILED JULY 9, 1915.

1,170,523.

Patented Feb. 8, 1916.

UNITED STATES PATENT OFFICE.

ADELBERT FERNALD, OF BOSTON, MASSACHUSETTS.

RIGHT-ANGLE NERVE-EXTRACTOR.

1,170,523.

Specification of Letters Patent.

Patented Feb. 8, 1916.

Application filed July 9, 1915. Serial No. 38,994.

To all whom it may concern:

Be it known that I, ADELBERT FERNALD, a citizen of the United States, residing at Boston, in the county of Suffolk and State 5 of Massachusetts, have invented certain new and useful Improvements in Right-Angle Nerve-Extractors, of which the following is a specification.

The present invention relates to the art 10 of dentistry and more particularly to a tool which can be used as a nerve extractor, root canal reamer or driller, and which embodies novel features of construction whereby the operator can work upon the back teeth without the necessity of bending and flexing the 15 tool, and can effectively operate the tool by manual means.

Further objects of the invention are to provide a tool of this character which is 20 comparatively simple and inexpensive in its construction, which admits of the various styles of tools being readily placed in position or removed therefrom, which is light and compact in its construction so 25 that it can be easily handled and manipulated, and which can be readily assembled and taken apart.

With these and other objects in view, the invention consists in certain novel combinations and arrangements of the parts as 30 will more fully appear as the description proceeds, the novel features thereof being pointed out in the appended claim.

For a full understanding of the invention 35 reference is to be had to the following description and accompanying drawing, in which:

Figure 1 is a side elevation of a dental tool constructed in accordance with the invention, showing a nerve extractor point as 40 fitted within the chuck. Fig. 2 is an enlarged vertical sectional view through the head of the tool. Fig. 3 is a similar view showing the manner of applying the finger piece to the main shaft. Fig. 4 is a horizontal sectional view taken on the line 4—4 of Fig. 2. Fig. 5 is an enlarged detail sectional view of the chuck, portions being broken away.

Corresponding and like parts are referred 50 to in the following description and indicated in all the views of the drawings by the same reference characters.

Specifically describing the present embodiment of the invention, the numeral 1

designates a tubular stock which has one end thereof exteriorly threaded at 1^a, while the opposite end thereof projects into a looped handle 3 which is secured to the sides of the stock. Extending through the tubular stock 1 and journaled therein is a main drive shaft 4, one end of the shaft having a small bevel gear 5 applied thereto, while the opposite end thereof projects beyond the stock 1 and has a cylindrical finger piece or sleeve 6 rigidly applied thereto. The exterior surface of the cylindrical finger piece or sleeve 6 is preferably milled or roughened so that it can be readily grasped by the fingers and the small set screw 7 is shown as 70 provided for securing the finger piece to the shaft. This finger piece is positioned within the looped handle 3, and one end thereof is preferably reamed out at 6^a so as to fit over the end of the stock 1 and obtain a bearing 75 thereon.

A sleeve 8 is fitted upon the threaded end 1^a of the stock 1, the diameter of the small bevel gear 5 being substantially the same as the exterior diameter of the stock 1 so that 80 the bevel gear 5 can be inserted through the bore of the sleeve 8. At the outer end of the sleeve 8 is a tubular head 9 which has the axis thereof arranged at right angles to the axis of the sleeve. A short tubular shaft 10 85 is journaled within the head 9, and the upper end of the bore of the head is reamed out or enlarged at 9^a to provide a chamber for a bevel gear 11 which is rigid with the tubular shaft 10 and normally meshes with 90 the before mentioned bevel gear 5 at the end of the main shaft 4. A cap piece 12 is threaded within the mouth of the enlarged upper end 9^a of the bore of the tubular head 9, said cap or plug being formed with a central opening 12^a to receive the upper end 95 of the tubular shaft 10, and being also provided with a kerf 12^b so that it can be readily engaged by a screw driver or like tool when being placed in position or removed 100 therefrom.

A chuck 13 extends through the tubular shaft 10 and is formed with an axial opening 14 adapted to receive the shank of a nerve extractor A or any similar tool. The 105 lower end of the chuck 13 terminates in a conical enlargement 15 and is longitudinally slotted at 16, while the upper end thereof is threaded for engagement with a milled thumb nut 17. The bore of the tubular shaft 110

10 has the lower end thereof flared at 10^a for coöperation with the inclined walls of the conical enlargement 15 at the end of the chuck 13 to force the jaws formed by the 5 slot 16 into a gripping engagement with the nerve extractor or like tool A when the chuck is drawn upwardly into the tubular shaft.

By loosening the thumb nut 17 the jaws 10 of the chuck 13 will be permitted to spring apart a sufficient amount to admit of the shank of any form of tool A such as a nerve extractor, root canal reamer, or driller being inserted into the bore of the tubular shaft 15 or withdrawn therefrom. After the shank of the desired form of tool A has been inserted into the bore of the chuck 13 the thumb nut 17 is tightened so as to draw the chuck upwardly into the tubular shaft and 20 cause the jaws thereof to be forced into a gripping engagement with the point by the cam action between the flared mouth of the tubular shaft 10 and the conical enlargement 15 at the slotted end of the chuck. When 25 tightening the thumb nut 17 the cylindrical finger piece 6 is grasped between the fingers so as to prevent rotation of the tubular shaft 10 and chuck 13 with the thumb nut.

After the desired style of tool A has been 30 inserted in the chuck, the desired rotary movement can be imparted thereto by rolling the cylindrical finger piece 6 between the fingers of the hand. The looped handle 3 provides a convenient means for holding 35 the tool in proper position while manipulating the same, and the working tool A is disposed at right angles to the stock and handle so that the operator can work upon the back teeth without the necessity of flexing the tool in the usual manner. This is a 40 great advantage, since a tool often has to be bent at substantially right angles to the handle when being used upon the back teeth and

under these conditions the tool not infrequently breaks when rotated.

An important feature of the hand operated right angle nerve extractor, root canal reamer and driller is that the chuck is so constructed that it will hold any make, any size, and any length required of broaches, 50 reamers, and drills. When using the drills and broaches the tools may be cut off at suitable lengths before inserting them into the chuck. When the instrument is thus constructed, fine broaches, drills, and reamers can more readily follow the irregular 55 nerve canal, without being broken, and this is very important, since, otherwise there would be danger of drilling through the sides of the root.

Having thus described the invention, what I claim as new and desire to secure by Letters Patent, is:—

A dental drill of the character described, including a tubular stock, a flat looped handle projecting longitudinally from one end of the tubular stock, a head upon the opposite end of the tubular stock, a main shaft extending longitudinally through the tubular stock and journaled therein, one end of 70 the main shaft projecting into the interior of the looped handle, a finger operated sleeve rigidly applied to the said end of the main shaft and arranged within the confines of the flat looped handle so as to be readily engaged by the fingers of the hand grasping the handle, and a chuck mounted within the head and geared to the opposite end of the main shaft.

In testimony whereof I affix my signature 80 in the presence of two witnesses.

ADELBERT FERNALD.
